UNITED STATES PATENT OFFICE.

THOMAS F. GALLIGAN, OF PROVIDENCE, RHODE ISLAND.

COIN-SORTER.

937,517.

Specification of Letters Patent. Patented Oct. 19, 1909.

Application filed January 13, 1909. Serial No. 472,042.

To all whom it may concern:

Be it known that I, THOMAS F. GALLIGAN, a citizen of the United States, and a resident of Providence, in the county of Providence and State of Rhode Island, have invented a new and Improved Coin-Sorter, of which the following is a full, clear, and exact description.

This invention is an improved apparatus for automatically separating coins according to their several denominations, and may be defined as consisting of a series of annular passages arranged one below the other and each having an outlet for coins of one 10 nomination, the bottom wall of each passage having a coin-delivery opening to the passage beneath, said delivery openings successively decreasing in size from the top passage to the bottom passage, in accordance with the size of the coins, a coin carrier in each passage, having perforated coin pockets of a size equal to or slightly greater than the largest coins which are received into the passage, means for sweeping the coins into 20 the pockets of each carrier, and means for revolving the carriers in a direction to first move the coins under the sweeping means, thence over the discharge openings, and finally carry those coins remaining in the 25 pockets over the several denomination outlets whereby the coins drop through by gravity.

Reference is to be had to the accompanying drawings forming a part of this specification, in which similar characters of reference indicate corresponding parts in all the views.

Figure 1 is a perspective view of a coin sorter embodying my invention; Fig. 2 is a 40 concentric vertical section of the same substantially on the line 2—2 of Fig. 4, looking in the direction of the arrow; Fig. 3 is a central vertical section of the coin sorter on the line 3—3 of Fig. 5; Fig. 4 is a sectional plan of the same approximately on the line 4—4 of Fig. 3; Fig. 5 is a plan of the coin sorter with the primary delivery chute removed; and Fig. 6 is a vertical central section through the lower portion of the sorter, 45 approximately on the line 6—6 of Fig. 5.

I preferably construct the body of my improved coin sorter in the nature of an upright cylinder composed of a series of separable cup sections 10 seating on and interfitting one with the other and dividing the

cylinder into as many compartments as there are sizes of coins, by reason of the bottoms or heads 11 of the sections. The top section 10, which is shown relatively higher than the other sections, is provided with a 60 brace-bar 12, in which is journaled, as also in the wall of the cylinder, a shaft 13 having an exteriorly-arranged operating crank 15. To the inner end of the shaft 13 is attached a bevel pinion 16 meshing with a 65 similar pinion 17 secured to the upper end of a central vertical shaft 18, the latter being journaled at its upper end in a central cross-bar 18^a, also extending across the upper section of the cylinder. 70

For each compartment or section of the cylinder, except the top section, a cylindrical box or wheel 19 is secured to the shaft 18, successively increasing in diameter in passing from the upper to the lower compartment and forming the several compartments into as many annular passages 20, successively decreasing in width in passing downwardly. Each box has a coin carrier 21 suitably attached to its under side and bearing on one of the heads 11. These carriers have coin holders or pockets which are made by perforating the margins of the plates of which the carriers are formed, the perforations 22 successively decreasing in size 80 in passing from the top carrier to the bottom carrier; in accordance with the sizes of the coins of the several denominations; thus, for example, the perforations in the carriers in passing from the top to the bottom will be 85 of a size to receive a dollar, half dollar, quarter, five cent piece, one cent piece and a ten cent piece. The heads 11 forming the bottoms of the passages have coin-discharge 90 openings 23, one of which is shown in dotted outline in Fig. 4, and another in Fig. 6, in the bottom of the cylinder, the latter serving for the ten cent piece or smallest coin. The openings 23 are in the nature of slots, and their width decreases in passing from 95 the bottom of the first to the bottom of the last passage, in accordance with the size of the coins, thus all of the coins but the dollar can drop through the discharge opening in the bottom of the upper passage; all of the 100 coins but the half dollar can drop through the discharge opening in the bottom of the succeeding passage, and so on.

In addition to the coin-discharge openings, the passages also have what I term 110

denomination outlets, all of which except that for the bottom passage extend through the side of the cylinder or casing, as shown in Fig. 3, and are arranged one in advance of the other as shown in Figs. 4 and 5. The denomination outlet for all but the bottom passage, as shown in Fig. 3, is made by forming the adjacent head 11 with a downwardly and outwardly-inclined lip or chute 24 which discharges into the upper end of a conveying tube 25, the latter leading to a money drawer or other suitable receptacle.

In each annular passage 20, at that side of the chute 24 from which the coin carrier revolves, is arranged a stationary guard-plate 26, one of which is shown in dotted outline in Fig. 5, which prevents the coins after dropping through the coin-discharge opening above from passing in the opposite direction to the revolution of the carrier and dropping directly into the chute. In this manner they are enforced to travel under a sweeping brush 27 located with respect to the discharge opening and denomination outlets, as illustrated in dotted outline in Fig. 5, such a brush being arranged in each passage in approximately the same position with respect to its opening and outlet and secured in fixed position to the head 11. At the front of each brush is also fixed a depending guard-plate 28, as best shown in Fig. 2, which assists in sliding the coins in the coin holders preparatory to passing under the brushes, where they are enforced to each pass into a separate pocket. From Figs. 5 and 6 it will be seen that the coin-discharge opening 23 for any passage is arranged directly at the rear of its brush.

In the top of the cylinder is a general delivery chute 29 for all of the coins, the said chute covering the mechanism in the cylinder therebelow and discharging into the opening 23 in the top head, the coins falling on the top carrier directly in advance of the guard-plate and brush. On revolving the crank in the proper direction, the carrier will first move the coins underneath the brush, where they will be swept into the pockets and thence pass over the coin-discharge opening in the top head, and through this opening all coins will drop, with the exception of the largest coin, generally the dollar, which will continue to travel in the passage until the top chute 24 is reached, where it will drop out into the connecting conveying tube 25. This operation will be successively repeated in the coin passages below until the last passage is reached, which will receive the smallest coins through the coin-discharge opening from the passage above. These smallest coins will be swept into the pockets of the carrier and pass through the discharge opening 23 in the bottom of the cylinder.

65 By reason of the sectional construction of

the cylinder, the sorter may be easily taken apart for repairs, etc. and built up to separate coins, checks, etc. of any size.

Having thus described my invention, I claim as new and desire to secure by Letters Patent:

1. The combination of a casing having a series of annular passages arranged one above the other and each having an outlet for coins of one denomination, with the bottom wall of each passage having a coin-delivery opening to the passage beneath, said delivery openings successively decreasing in size in passing from the top to the bottom passage, in accordance with the size of the coins, and a coin carrier in each passage revoluble in a direction to first move the coins over the discharge opening and then carry those remaining directly over the denomination outlet whereby they drop there-through by gravity.

2. The combination of a series of revoluble coin carriers, means for discharging all of the coins from each carrier at a single point to the next succeeding carrier, except coins of one size, and means for discharging the remaining coins at another point, in the revolution of the carrier.

3. The combination of an upright cylinder having a series of heads therein one above the other, each head having a coin-discharge opening and an outlet for coins of one denomination, a central vertical shaft journaled in the cylinder, a cylindrical box secured to the shaft underneath each head and forming in connection with the cylinder a series of annular passages, a coin carrier secured to each box having a series of coin pockets arranged to receive the coins face down, with the pockets decreasing in diameter in passing from the top to the bottom carrier and arranged in the path of the discharge openings and outlets, and means for revolving the shaft to carry the coins of each carrier first to the discharge opening and thence carry the remaining coins over the outlet.

4. The combination of a series of coin carriers arranged one below the other, each carrier having a series of marginal coin pockets, heads over which the coin carriers move, the heads having coin-discharge openings and coin outlets arranged at different points, brushes for sweeping the coins into the pockets, fixed relatively to said heads and arranged over the carriers between their respective outlets and discharge openings, with the brushes further arranged one in advance of the other in passing from the bottom carrier to the top carrier, and means for revolving the carriers in a direction to first move the pockets over the discharge openings and thence over the outlets.

5. The combination of an upright cylinder having a series of heads secured therein, ar-

ranged one above the other, a cross-bar in the upper portion of the cylinder between the heads, a central vertical shaft journaled in the cross-bar, a brace-bar arranged below 5 and at one side of the cross-bar, a driving shaft journaled in the brace-bar and extended to the outside of the cylinder, a crank attached to the outer end of the driving shaft, gearing operatively connecting said 10 shafts together, a cylindrical box secured to the central vertical shaft below each head, a coin carrier attached to the under side of each box and bearing on the adjacent head, having marginal coin pockets, each head 15 having a coin-discharge opening and an outlet for coins of one denomination, arranged in the path of the coin pockets of the adjacent carrier, a brush secured to each head for sweeping the coins into the pockets of the 20 carriers, a guard arranged at the front of each brush, and a chute in the top of the cylinder for delivering the coins to the upper carrier.

6. The combination of an upright casing 25 divided into a series of annular passages arranged one above the other, the bottom of each passage having a coin-delivery opening to the next lower passage and provided with an outlet for coins of one denomination, 30 passing to the outside of the casing through the passage beneath, and a revoluble coin carrier in each passage for moving the coins first over the coin-delivery opening and thence over the denomination outlet.

7. The combination of an upright casing 35 having heads therein arranged one above the other, dividing it into a series of compartments, with the head of each compartment having a coin-delivery opening and an outlet for coins of one denomination, and a coin 40 carrier revoluble in each compartment and having coin pockets movable over said delivery opening and outlet.

8. The combination of an upright casing 45 having heads arranged one above the other, forming a series of compartments, each head having a coin-delivery opening and a denomination outlet, a central vertical shaft revoluble in the casing, having a cylindrical box secured thereto in each compartment, 50 forming in conjunction with the casing an annular passage, said boxes increasing in diameter from the top to the bottom, whereby the passages increase in width from bottom to top, and a rotary carrier movable with the 55 shaft and boxes, arranged in each passage adjacent to its respective head and having pockets successively movable over the coin-delivery opening and the denomination outlet. 60

In testimony whereof I have signed my name to this specification in the presence of two subscribing witnesses.
